LOCK FOR SLIDING DOORS OF RAILWAY CARS

Albert S. Noble, Parma, Ohio, assignor to The Youngstown Steel Door Company, Cleveland, Ohio, a corporation of Ohio

Application November 23, 1954, Serial No. 470,648

4 Claims. (Cl. 292—283)

This invention relates to locks for sliding doors of railway cars.

It is an object of this invention to provide locks for sliding doors of railway cars which shall be capable of compensating for inaccuracies of application of the locks.

A further object is to provide locks for sliding doors of railway cars which shall be capable of compensating for shifting of the locks after application.

A further object is to provide locks of the hasp and pin type for sliding doors of railway cars wherein the locks shall be so constructed that the hasp can be projected or retracted relative to the pin.

A further object is to provide locks for sliding doors of railway cars so constructed that the locking relationship of the locks may be simply and properly established and subsequently restored without removing the locks from the cars or modifying the locks.

Other objects of the invention will become clear as the description thereof proceeds.

In the drawings forming part of this specification:

Fig. 1 is an elevation of a lock embodying the instant invention applied to a sliding door of a railway car, the door being shown fragmentarily.

Fig. 2 is a horizontal section taken on line 2—2 of Fig. 1.

Fig. 3 is a view similar to Fig. 1 showing the hasp of the lock in projected position.

Fig. 4 is a view similar to Fig. 1 showing the hasp of the lock in retracted position.

In the drawings the numeral 10 designates a door of well known construction embodying a metallic panel 11 formed with horizontal corrugations 12. The door 10 which is shown fragmentarily is illustrated in closed position and secured by means of a lock embodying the instant invention. In such position the door engages a front stop 13 which is riveted to a front door post 14 partially shown in the drawings. The door post 14 forms part of the side wall of a railway freight car which also embodies metallic sheathing 15 secured to the door post by the same rivets which fasten the front stop 13 thereto.

In order to secure the door in closed position, a lock 16 embodying the instant invention is utilized. This lock embodies a hasp fastener 17 disposed upon the outside of one of the horizontal corrugations 12 and reinforced by a member 18 lying upon the inside of the corrugation. The hasp fastener and its reinforcement are secured to the corrugation by means of rivets 19. The hasp fastener 17 is formed with a gooseneck portion 20, the end 21 of which extends through the metallic panel 11 and the hasp fastener reinforcing member 18 as illustrated in Fig. 2 of the drawing.

The lock 16 embodies a hasp 22 which is formed with an eye 23 and a box section 24 through which a vertically disposed locking pin 25 is adapted to extend when the lock is in locking position. The eye 23 of the hasp is round and an eccentric disk 26 is seated therein. This disk is formed with a circumferential flange 27 which overlaps the eye of the hasp and which may be welded

2

to the hasp if desired. Notches 28 are formed in the flange 27 of the disk so as to aid in rotating the disk relative to the eye of the hasp when this becomes necessary. The end 21 of the hasp fastener extends through the eccentric opening 29 formed in the disk 26 so as to swingably support the hasp.

The lock 16 further embodies a lock bracket 30 which is secured as by means of rivets 31 to the door post 14 of the car side. The lock bracket which is preferably in the form of a casting embodies vertically spaced housings 32 and 33 through which the pin 25 is adapted to extend. When the hasp is in locking position the pin also extends through the box section 24 thereof so as to prevent opening movement of the door. As illustrated the pin preferably is one which has a straight side 34 adapted to bear against the lock bracket and a tapered side 35 which is adapted to be engaged by a similarly tapered wall 36 of the box section of the hasp.

The lock bracket 30 carries opening and closing lever 37 which is pivotally supported in a vertical position at the lower housing member 33. The lever 37 is formed with a lug 38 which is adapted to be received within a recess 39 formed in the hasp fastener and to cooperate with the walls of this recess in order to impart initial opening and final closing movements to the door as is well known.

Fig. 1 illustrates the desired relationship between the hasp and the pin when the door is locked and the corresponding position of the eccentric disk 26. In order to obtain the illustrated relationship between the hasp and the pin prior to applicant's invention a time-consuming adjustment of the lock bracket or of the hasp fastener or hasp was frequently required. This is obviated by the instant invention. If the illustrated position of the lock bracket and the pin is not obtained at the time that the lock bracket is applied to the car side, it only becomes necessary to rotate the eccentric disk 26 within the eye of the hasp in order to project or retract the hasp as may be required to establish the desired relationship between the hasp and the pin. Where the disk has been secured to the eye of the hasp fastener by a spot of weld material, this weld is first broken away in order to permit the desired rotation of the eccentric disk.

Fig. 3 of the drawing illustrates the hasp in its extreme projected position. This may occur after the railway car has been placed in service as a result of the shifting of the hasp fastener or for other reasons which occurs when the car is subjected to impact. It will be observed from Fig. 3 of the drawings that when such shifting occurs the pin 25 is permitted to fall to its lowermost position so that all of the take-up which the shape of the pin normally permits is lost. When this has occurred the door can lash back and forth upon its supporting track so that wear in the parts of the lock will occur as is well known in the art.

In order to restore the take-up of the lock the eccentric disk 26 is rotated counterclockwise. Such rotation of the eccentric disk causes the hasp fastener to be retracted or moved toward the right as viewed in Fig. 3 of the drawings. This permits the pin to be raised so that the take-up which it provides is restored.

Fig. 4 of the drawing illustrates the position of the hasp and the relative position of the pin when the hasp has been retracted to its extreme position. To establish this relationship the eccentric disk 26 has been rotated counterclockwise from its position shown in Fig. 3 of the drawing to the position shown in Fig. 4. It will be understood, of course, that the degree of rotation of the eccentric disk will depend upon the extent to which the take-up provided by the tapered pin is to be restored.

While the invention has been illustrated and described in connection with a take-up lock, it will be apparent

that it is applicable as well to locks which employ straight pins.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. A lock for sliding doors of railway cars comprising a lock bracket adapted to be secured to a car, a locking pin slidably carried by said bracket and having a side adapted to bear against said bracket and a downwardly and inwardly sloping side, a hasp fastener adapted to be secured to a door, a hasp having an eye, a wall on said hasp sloping similar to and engageable with said sloping side of said pin, and a disk seated in said eye and having an eccentrically disposed opening therein, said hasp fastener having a portion extending through said eccentrically disposed opening in said disk and swingably supporting said hasp, said disk being rotatable within said eye and about said extending portion of said hasp fastener to project or retract said hasp and move said wall of said hasp away from or toward said sloping side of said pin.

2. A lock for sliding doors of railway cars comprising a lock bracket adapted to be secured to a car, a locking pin slidably carried by said bracket and having a side adapted to bear against said bracket and a downwardly and inwardly sloping side, a hasp fastener adapted to be secured to a door, a hasp having an eye, a wall on said hasp sloping similar to and engageable with said sloping side of said pin, and a disk seated in said eye and having an eccentrically disposed opening therein, said hasp fastener having a portion extending through said eccentrically disposed opening in said disk and swingably supporting said hasp, said disk being rotatable within said eye and about said extending portion of said hasp fastener to project or retract said hasp and move said wall of said hasp away from or toward said sloping side of said pin, said disk having a flange overlapping said hasp, and welding securing said flange to said hasp after the disk has been rotated to the desired position.

3. A lock for sliding doors of railway car comprising a lock bracket adapted to be secured to a car, a locking pin slidably carried by said bracket and having a side adapted to bear against said bracket and a downwardly and inwardly sloping side, a hasp fastener adapted to be secured to a door, a hasp having an eye, a wall on said hasp sloping similar to and engageable with said sloping side of said pin, and a disk seated in said eye and having an eccentrically disposed opening therein, said hasp fastener having a portion extending through said eccentrically disposed opening in said disk and swingably supporting said hasp, said disk being rotatable within said eye and about said extending portion of said hasp fastener to project or retract said hasp and move said wall of said hasp away from or toward said sloping side of said pin, said disk having a flange overlapping said hasp, slots formed in said flange, and welding securing said flange to said hasp after said disk has been rotated to the desired position.

20 4. A lock for sliding doors of railway cars comprising a lock bracket adapted to be secured to a car, a locking pin slidably carried by said bracket and having a side adapted to bear against said bracket, a hasp fastener adapted to be secured to a door, a hasp having an eye, said hasp having a wall engageable with the opposite side of said pin, and a disk seated in said eye and having an eccentrically disposed opening therein, said hasp fastener having a portion extending through said eccentrically disposed opening in said disk and swingably supporting said hasp, said disk being rotatable within said eye about said extending portion of said hasp fastener to project or retract said hasp and move said wall of said hasp away from or toward said opposite side of said pin.
